UNITED STATES PATENT OFFICE.

JESSE ALEXANDER, OF NEW YORK, N. Y.

DESIGN FOR A TYPE-WRITING-MACHINE FRAME.

44,348.

Specification for Design.

Patented July 22, 1913.

Application filed June 22, 1911. Serial No. 634,829. Term of patent 14 years.

To all whom it may concern:

Be it known that I, JESSE ALEXANDER, a citizen of the United States, and resident of New York, in the county of Kings and State of New York, have invented a new, original, and ornamental Design for Type-Writing-Machine Frames, of which the following is a specification, reference being had to the accompanying drawings, forming part thereof.

Figure 1, is a front perspective view of

a frame embodying my invention looking down upon it from the left. Fig. 2, is a rear perspective view of the same looking down upon it from the right.

What I claim is:—

The ornamental design for a typewriting machine frame, as shown.

JESSE ALEXANDER.
